BY D. A. Co. ATTY'S.

UNITED STATES PATENT OFFICE.

EDWIN R. CAHOONE, OF NEWARK, NEW JERSEY.

DESIGN FOR A BRIDLE-FRONT.

SPECIFICATION forming part of Design No. 17,514, dated August 2, 1887.

Application filed June 9, 1887. Serial No. 240,714. Term of patent 7 years.

To all whom it may concern:

Be it known that I, EDWIN R. CAHOONE, a citizen of the United States, residing at Newark, in the county of Essex and State of New Jersey, have invented and produced a new and original Design for Bridle-Fronts; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figures 1 and 2 are front views of a portion of a bridle-front embracing my design. Fig. 3 is a plan of a complete bridle-front, and Fig. 4 is a sectional view taken transversely therethrough.

The leading feature of the design consists in a bridle-front, which comprises a bridle-front with ribs *b b* at its upper and lower edges, between which are displayed ornamental spirals extending transversely across the recess formed by the ribs in the face of said bridle-front from one rib to the other, substantially as will be hereinafter shown, described, and finally embodied in the clause of the claim.

In said drawings, *a* indicates a bridle-front, with longitudinal ribs *b b* extending along the upper and lower edges of the same in parallel lines. Between said ribs is a longitudinal recess, *c*. *d* is an ornamental spiral wire displayed within said recess along the front face of the bridle-front. The exposed or outer portions of the individual spirals of said wires lie a little apart parallel with one another, ex-

tending transversely across the recess from one rib to the other. When viewed in transverse sections, the wires or spirals are shown to fill the recess or extend from the upper rib to the lower one, or approximately so, and to extend or project above or beyond the edges of the said ribs, the bridle-front thus being curved or convex in its general outer or front face contour, as indicated in Fig. 4. When viewed in front elevation, as in Figs. 1 and 2, the convex outer or face portions of the spirals are shown or appear to extend diagonally straight across from rib to rib, as distinguished from a laterally-curved extension, occasioned by bending the individual spirals or helices down one upon the other, the said outer portions, when viewed directly from the front, presenting the appearance of a series of straight or approximately straight lines running diagonally from one rib to the other.

Having thus described the invention, what I claim as new is--

The design for a bridle front herein shown and described, which comprises a bridle-front with ribs *b b* at its upper and lower edges, between which the ornamental spirals extend diagonally across the recess from one rib to the other in straight parallel lines when viewed in front elevation, substantially as described. 65

In testimony that I claim the foregoing I have hereunto set my hand this 3d day of June, 1887.

EDWIN R. CAHOONE.

Witnesses:

CHARLES H. PELL,
OSCAR A. MICHEL.
